Primary Examiner — Darlington Ly(74) *Attorney, Agent, or Firm* — Barnes and Thornburg LLP**(57) CLAIM**

We claim the ornamental design for a ride-on tricycle, as shown and described.

DESCRIPTION

FIG. 1 is a top, front, and left side perspective view of a ride-on tricycle showing our new design;
 FIG. 2 is a bottom, rear, and right side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the drawings illustrate portions of the ride-on tricycle that form no part of the claimed design.
